CLAIM

The ornamental design for a gaming table, as shown and described.

DESCRIPTION

FIG. 1 is a perspective view of a gaming table showing my new design;

FIG. 2 is a top plan view thereof;

FIG. 3 is a front elevational view thereof; the rear elevational view being a mirror image thereof;

FIG. 4 is a left side elevational view thereof; the right side elevational view being a mirror image thereof; and,

FIG. 5 is an enlarged scale top plan view thereof; with a pivoting, rotating holder being removed to illustrate the surface ornamentation on an upper surface.

The bottom is plain and unornamented.
